COMBINED CIGARETTE BOX AND MATCH PACKAGE

Masamitsu Ishihara, 628 Hirai, Kannami-cho,
Tagata-gun, Shizuoka-ken, Japan

Filed Mar. 15, 1973, Ser. No. 341,582

Term of patent 14 years

Int. Cl. D9—193

U.S. Cl. D9—193

FIG. 1

FIG. 2

FIG. 4

FIG. 1 is a top, front perspective view of a combined cigarette box and match package showing my new design, with the match flap partially opened;

FIG. 2 is a bottom, rear perspective view thereof;

FIG. 3 is a side elevational view thereof; and

FIG. 4 is a view similar to FIG. 1 with the match flap fully opened.

I claim:

The ornamental design for a combined cigarette box and match package, as shown.
